(57) CLAIM

I claim the ornamental design for a weed extraction tool, as
shown and described.

DESCRIPTION

FIG. 1 is a front and left side isometric view of a first
embodiment of my weed extraction tool;

FIG. 2 is a left side view thereof;

FIG. 3 is a front view thereof;

FIG. 4 is a right side view thereof;

FIG. 5 is a rear view thereof;

FIG. 6 is a top view thereof;

FIG. 7 is a bottom view thereof;

FIG. 8 is a front and left side isometric view of a second
embodiment of my weed extraction tool;

FIG. 9 is a left side view thereof;

FIG. 10 is a front view thereof;

FIG. 11 is a right side view thereof;

FIG. 12 is a rear view thereof;

FIG. 13 is a top view thereof;

FIG. 14 is a bottom view thereof.

FIG. 15 is a front and left side isometric view of a third
embodiment of my weed extraction tool;

FIG. 16 is a left side view thereof;

FIG. 17 is a front view thereof;

FIG. 18 is a right side view thereof;

FIG. 19 is a rear view thereof;

FIG. 20 is a top view thereof; and,

FIG. 21 is a bottom view thereof.
